MINIATURE MOTOR BOAT

Jules J. Klein, Fort Lauderdale, Fla., assignor to Hydro-glas Industries, Inc., Detroit, Mich., a corporation of Michigan

Filed Oct. 17, 1967, Ser. No. 9,028

Term of patent 14 years

(Cl. D71—1)

FIG. 1

FIG. 2

FIG. 3

FIG. 4

FIG. 5

FIG. 6

FIG. 7

FIG. 9

FIG. 8

FIG. 1 is a side elevation of a miniature motor boat showing my new design.

FIG. 2 is a plan view thereof.

FIG. 3 is a front elevational view thereof.

FIG. 4 is a bottom plan view thereof.

FIG. 5 is a rear elevational view thereof.

FIG. 6 is a cross sectional elevational view taken through section line 6-6, FIG. 1.

FIG. 7 is a cross sectional side elevation taken through section line 7-7, FIG. 2.

FIG. 8 is a cross sectional rear elevation taken through section line 8-8, FIG. 1.

FIG. 9 is a cross sectional rear elevation taken through section line 9-9, FIG. 1.

The dominant features of my design reside in the portions shown in full lines.

I claim:

The ornamental design for a miniature motor boat, as shown and described.
